UNITED STATES PATENT AND TRADEMARK OFFICE
Certificate

Patent No. Des. 372,034

Patented: July 23, 1996

On petition requesting issuance of a certificate for correction of inventorship pursuant to 35 U. S. C. 256, it has been found that the above-identified patent, through error and without deceptive intent, improperly sets forth the inventorship.

Accordingly, it is hereby certified that the correct inventorship of this patent is: James J. Handzel, New Hope, Minn.; Kent P. Hand, Coon Rapids, Minn.; Bradley K. Voigt, Big Lake, Minn.; Scott C. Losey, Minneapolis, Minn. and Thomas E. Pauly, Roseville, Minn.

Signed and Sealed this Seventh Day of October, 1997.
